(57) **CLAIM**

The ornamental design for a footwear with a scallop design, as shown and described.

DESCRIPTION

FIG. 1 is a perspective view of my footwear with a scallop design;

FIG. 2 is a first side view thereof;

FIG. 3 is a second side view thereof;

FIG. 4 is a top view thereof;

FIG. 5 is a bottom view thereof;

FIG. 6 is a front view thereof; and,

FIG. 7 is a rear view thereof.

The broken line showing of the boot is included for the purpose of illustrating and forms no part of the claimed design.
